Primary Examiner — Cynthia Underwood(57) **CLAIM**

The ornamental design for combination of input device and protective cover, as shown and described.

DESCRIPTIONFIG. 1 is a perspective view of the combination of input device and protective cover;
FIG. 2 is a front view thereof;
FIG. 3 is a rear view thereof;
FIG. 4 is a left side view thereof;
FIG. 5 is a right side view thereof;
FIG. 6 is a top plane view thereof;
FIG. 7 is a bottom plane view thereof;
FIG. 8 is another perspective view thereof;
FIG. 9 is a front perspective view thereof in an alternate configuration of use; and,
FIG. 10 is a back perspective view thereof in an alternate configuration of use.

The broken lines in the drawings depict environmental subject matter/or parts of the combination of input device and protective cover and form no part of the claimed design.
